United States Patent Office

Des. 203,818
Patented Feb. 22, 1966

203,818

KNIFE OR SIMILAR ARTICLE

Benjamin Seibel, New York, N.Y., assignor to American Can Company, New York, N.Y., a corporation of New Jersey

Filed May 12, 1965, Ser. No. 85,246

Term of patent 14 years

(Cl. D22—3)

Fig. 3

Fig. 2

Fig. 1

I claim:

The ornamental design for a knife or similar article, substantially as shown.
